[57] CLAIM

The ornamental design for a tool handle, as shown and described.

DESCRIPTION

FIG. 1 is a top plan view of a tool handle showing our new design;

FIG. 2 is a side elevational view thereof, the opposite side being a mirror image;

FIG. 3 is a bottom plan view thereof;

FIG. 4 is a right end elevational view thereof;

FIG. 5 is a left end elevational view thereof;

The side of the tool handle not shown is a mirror image of FIG. 2.

FIG. 1

FIG. 2

FIG. 3

FIG. 4

FIG. 5
